UNITED STATES PATENT OFFICE.

WARREN R. COX, OF CLEVELAND, OHIO.

LOCK-SWITCH.

1,325,981.

Specification of Letters Patent. Patented Dec. 23, 1919.

Application filed July 14, 1916. Serial No. 109,376.

To all whom it may concern:

Be it known that I, WARREN R. COX, a citizen of the United States, residing at Cleveland, in the county of Cuyahoga and State of Ohio, have invented certain new and useful Improvements in Lock-Switches, of which the following is a specification.

My invention appertains more particularly to lock switches used to prevent the theft of automobiles, and the present device is an improvement in the locking means disclosed in my Letters Patent No. 1,015,300, dated January 23, 1912, and in my Patent No. 1,253,470 of Jan. 15, 1918.

In one type of lock-switch in general use, the practice is to provide a switch body made of insulating material. This body is secured to a coil-box and covered by a protecting plate at its front. A key is required to operate the switch and the protecting plate cannot be removed without the use of the same key. But the switch body in general use is breakable, and thefts of cars have occurred where the switch has been reached by demolishing the body. My improved device is designed to protect the switch body by inclosing the same with an extension forming an integral part of the protecting plate, and the device is modified also in other particulars, all as herein shown and described and more particularly pointed out in the claims.

In the accompanying drawings, Figure 1 is a front view of my improved lock-switch mounted upon the front of a coil box, and Fig. 2 is a similar view showing the lock switch in section and the coil box partly broken away to disclose the electrical units therein.

Fig. 3 is a sectional view of the associated parts on line 3-3, Fig. 2. Fig. 4 is a vertical section centrally through the coil box and lock switch, showing a key in place therein. Fig. 5 is a side view of the lock and a sectional view of the protecting shell affixed thereto.

Certain types of automobiles employ metal coil boxes 2 within which a series of electrical sparking units 3 are housed. This box is usually secured to the dash-board or within the cowl of the vehicle and is provided at its front with an electrical switch, comprising a chambered body 5 of insulating material carrying spring contacts 6 and a rotatable switch arm 7 to control two electrical circuits, termed the magneto and bat-

tery circuits, respectively. Arm 7 is mounted on a metal sleeve 8 having rotatable bearing on a fixed stud or shaft 9, and the front end of said sleeve is provided with a slot or slots 10 diametrically thereof, see Fig. 2, whereby the arm may be turned either to the right or left when the right-angled projections 11 of the rotatable barrel 12 of the lock are operatively engaged with said slots in the sleeve 8 as shown in Fig. 4. The projections 11 are flat and separated to straddle stud 9, being in effect a divided flat T-shaped extension of the barrel 12 which is rotatably mounted in the cylindrical housing 13 containing the spring-pressed locking pins 14. The barrel also contains a corresponding set of plungers 15 adapted to be engaged by the key 16 in unlocking and turning movements of the switch, but the locking pins and plungers must be in alignment as shown in Fig. 4 to effect locking of the barrel and withdrawal of the key. In this position of the parts, the intent also is to use the projections 11 to effect locking of the protecting shell 17 upon switch body 5, a result obtained in this structure by the use of a plate or disk 18 secured to the recessed front of switch body 5 by screws 19, see Fig. 2. Disk 18 has a central opening 20 affording an entrance for the projections 11 and permitting locking engagement of the projections with the inner face of the disk. The mounting or housing 13 is fastened to the shell 17 by screws 21, see dotted lines Fig. 3, and therefore when the barrel 12 is rotated by use of key 16 to place the projections in line with the edge slots 20 it is possible to remove the shell and lock jointly from the switch body 5, providing the extra fastening screws 22 which extend through the front face of the shell into the body are also removed.

Shell 17 comprises a face plate having a round reduced extension 23 at its front to confine the lock and an enlarged irregular-shaped extension 23' at its rear to inclose the switch body 5, and the inner locking disk 18 which is covered by the shell is cut away or extends only a short distance above the axial center of the switch body 5 to provide an opening 24 whereby access to the chambered interior of the body 5 may be gained to engage and remove the centrally-positioned locking screw 25 which extends through the coil box 2 and serves to lock the units 3 therein. To explain further, the

units 3 have channeled faces adapted to hold a set of locking bars 26 and the long locking screw 25, and when the shell is locked upon the switch body 5 the units cannot be taken out of box 2 nor can the switch be operated without the proper key. The metal inclosed body 5 makes it difficult to break the body into pieces by a hammer or other instrument and operation of the switch or 10 tampering with the wire connections for the coil box is effectively prevented.

What I claim is:

1. A body having a rotatable arm provided with a slotted bearing sleeve, a locking plate secured at the front of said body having a central opening adapted to coincide with the slots in said sleeve, and a metal shell inclosing the front and sides of said body having locking mechanism mounted

thereon provided with interlocking extensions for both said plate and sleeve. 20

2. In a lock switch, a chambered body of insulating material having switch mechanism therein, a radially slotted locking plate secured to said body and open to the interior 25 of the body above its axial center, a fastening screw within said body, a metal protecting shell completely inclosing the front and sides of said body having key locking means mounted thereon and extending 30 through said plate in interlocking relations therewith and with said switch mechanism.

In testimony whereof I affix my signature in presence of a witness.

WARREN R. COX.

Witness:

R. B. MOSER.
